UNITED STATES PATENT OFFICE.

WILLIAM J. BAYRER, OF SOUTHBINGHAM, CONNECTICUT, ASSIGNOR TO THE PECK, STOW & WILCOX COMPANY, OF SAME PLACE.

SHEARS FOR METAL.

SPECIFICATION forming part of Letters Patent No. 372,785, dated November 8, 1887.

Application filed August 1, 1887. Serial No. 245,800. (No model.)

To all whom it may concern:

Be it known that I, WILLIAM J. BAYREE, a citizen of the United States, residing at Southington, in the county of Hartford and State of Connecticut, have invented certain new and useful Improvements in Shears, of which the following is a specification.

My invention relates to the class of shears that are used for cutting sheet metal, such as are shown and described in an application for United States Letters Patent of even date herewith; and the object of my invention is to provide shears of this class with means for cutting stove-pipes or the like thin metal hollow ware.

Referring to the accompanying drawings, Figure 1 is a side view of my improved shears, and Fig. 2 is a front elevation of the same with the mandrel or rest removed.

In the drawings, the letter *a* denotes the bed, and *b* a horn rising from the bed and adjustably attached to it.

The letter *c* denotes a shaft that is borne in a suitable chamber in the end of the horn, and on the shaft are a number of teeth that mesh with a rack which is attached to the blade-bearing plate *d*, this blade-bearing plate *d* being held in sliding contact with the end of the horn *b*. The shaft is provided with a lever whereby it may be oscillated; also, adjustable stops to limit the extent of oscillation of the shaft.

The above mechanism and its arrangement, but of a different form of bed, being fully described in my United States application before mentioned, a detail description here is unnecessary, and any other known mechanism for operating the blade-bearing plate may be substituted therefor.

An arm, *e*, extends from the bed *a* in line with the horn *b*, and on the end of said arm in position to act with the reciprocating cutter *d* is secured, preferably by a single bolt, a cutter, *f*, having a circular edge, and in the preferred style forming a complete circle. This arm *e* is provided with a perforation, *e'*, which also extends through the cutter *f*, into which the shaft *g'* of the mandrel or rest *g* is inserted when it is desired to support a long piece of pipe while it is being cut. The gage *h* is used

to determine the length of the section to be cut when cutting pipe, or to determine the width of a strip of metal. The shaft *h'* of this gage is free to slide in the bearing in the lug that projects from the bed when not clamped by the screw *h''* and held firmly with the face of the gage at any distance from the cutters when the screw is driven in.

Besides the advantages of adjustability, ease of operation, and accuracy of gaging incident to the device described in my application previously referred to, this tool has the advantage of being capable of use as a hollow-ware and pipe cutter.

In order to cut strips of metal the gage *h* is adjusted to the desired position and the metal fed lengthwise between the cutters with one edge bearing against the gage. When a section of pipe is to be cut, the gage *h* is set at a distance from the blades equal to the length to be cut off, the rest *g* put in place, and the pipe thrust over the arm *e* and circular cutter until the end strikes the face of the gage. Then the cutter *d* is reciprocated in the usual manner, rolling the pipe a little after each cut to bring a fresh place under the reciprocating blade. The cutter *f* and rest *g* form a mandrel to retain the shape and configuration of the pipe when used this way, as well as serving as a rest to support the article cut in the proper position. If short lengths of pipe or hollow ware are to be trimmed or cut by these shears, the rest *g* is removed and the cutter *f* alone acts as support, mandrel, and cutter. Another advantage results from providing a circular cutter in that it can be rotated and a new portion of the periphery presented to perform the cutting when one place becomes dulled by use. With my shears pipes and analogous articles can be cut off squarely with a smooth edge.

I claim as my invention--

1. The combination, in shears of the within-described class, of the reciprocating cutter and a cutter having a circular edge, all substantially as described, and for the purpose set forth.

2. The combination, in shears of the within-described class, of the reciprocating cutter and a circular complementary cutter rotarily attached to a projection from the bed, all substantially as described, and for the purpose set forth.

3. In shears, the combination of a bed, a horn projecting from the bed and bearing a shaft, a lever attached to the shaft and having adjustable stops, a cutter connecting with and 5 adapted to be reciprocated by the oscillation of the shaft, an arm projecting from the bed, and a circular cutter secured to said arm, all substantially as described, and for the purpose set forth.

4. In shears, the combination of a bed, a horn projecting from the bed and bearing a reciprocating cutter and its operating mechanism, an arm projecting from the bed, a cutter having a circular edge and secured to said

arm, and the rest *g*, all substantially as described, and for the purpose set forth.

5. In shears, the combination of a bed, a horn projecting from the bed and bearing a reciprocating cutter and its operating mechanism, an arm projecting from the bed, a cutter 20 having a circular edge and secured to said arm, and the gage *h*, all substantially as described, and for the purpose set forth.

WILLIAM J. BAYERER.
